UNITED STATES PATENT OFFICE

2,481,702

AIR CIRCULATING DEVICE

Charles W. Towt, Los Angeles, Calif., assignor to
Charles Kincheloe Towt, Los Angeles, Calif.

Application May 27, 1946, Serial No. 672,665.

9 Claims. (Cl. 230—258)

1

The invention relates to air circulators and has particular reference to a fan or air propeller of relatively large capacity designed to be mounted upon a tower for circulating air over large areas such as orchards, vineyards and cultivated fields.

It has been known and appreciated for some years that the growth of certain orchard crops can be assisted and stimulated by circulation of air. It has been demonstrated that air in certain fruit growing sections, particularly, has a tendency to stratify, and where there is not a sufficient natural circulation of air for long periods of time certain circumstances prevail which, for example, may prevent satisfactory pollination during blossom time or which during the cold seasons may permit a strata of air which is too cold to cling to the area where the trees are located. It has, moreover, been satisfactorily demonstrated that when the stratified air is broken up and circulated pollination is increased, fruit yield is increased and the effects of killing frosts are minimized. Other advantages also may be enjoyed which depend upon the circulation of air such as distribution of certain types of insecticide.

It has been found, moreover, that propellers of large capacity mounted upon towers can be effectively used for inducing an artificial circulation of air. Care, however, must be taken to provide a circulation of air having sufficient volume and a properly regulated velocity and direction, since improper circulation may be more damaging than beneficial.

It is, therefore, among the objects of the invention to provide a new and improved air circulating device which can be mounted at a sufficient height above the ground and which is so constructed that it is capable of providing a large volume of air for circulation over a relatively large area, properly controlled and directed so that the beneficial results described above may be attained.

Another object of the invention is to provide a new and improved air circulating device which is simple in design and construction permitting it to be prefabricated with respect to its individual parts, readily crated and shipped, and easily assembled at the site.

Another object of the invention is to provide a new and improved air circulating device which is adapted to be mounted upon a tower in a manner permitting air to be directed in any direction throughout a 360° arc.

Still another object of the invention is to pro-

2

vide a new and improved air circulating tower wherein the motor source may consist of a combustion engine completely controlled from a location near the ground.

Still further among the objects of the invention is to provide a tower for mounting an engine adapted to drive an air propeller wherein the engine may be geared to a suitable drive so that the engine is rotated at the same time and from the same source as the motive power which drives the propeller; there being further provided a hollow shaft in the tower for anchoring the engine rotatably upon the tower which may also be utilized as a gas tank and through which may extend, if desired, necessary controls for the motor which are adapted to rotate with the motor and thereby leave the motor entirely free for continued 360° rotation.

With these and other objects in view, the invention consists in the construction, arrangement and combination of the various parts of the device whereby the objects contemplated are attained, as hereinafter more fully set forth, pointed out in the claims and illustrated in the accompanying drawings, in which:

Figure 1 is a side, elevational view of a tower showing an engine operated propeller rotatably mounted upon the top.

Figure 2 is an enlarged, longitudinal, sectional view of the upper portion of the tower and engine taken on the line 2—2 of Figure 1.

Figure 3 is a side, elevational view of the engine and the engine support showing details of the drive adapted to rotate the engine.

Figure 4 is a fragmentary, longitudinal, sectional view taken on the line 4—4 of Figure 3.

Figure 5 is a fragmentary, plan view taken on the line 5—5 of Figure 3.

Figure 6 is a cross-sectional view showing a portion of the platform on the top of the tower.

Among the features desired in a wind tower or air circulating device adapted to the purpose described herein is to construct a tower in such a way that it can be readily shipped to a suitable location in some orchard and there assembled by the purchaser without it being necessary to engage steel erection men or persons specially skilled in the installation of devices of this sort.

In order that the device may be operated efficiently, it must be of such simple and rugged construction as to provide few parts which become worn or which can get out of order. Since these devices must be operated spasmodically whenever desired and be placed in operation or discontinued from operation without great loss of time, it is

highly desirable to have the necessary controls located on the ground, although the working parts of the machine may be more advantageously located high up on the tower above the ground.

Versatility of operation and manipulation is a highly desirable feature in the design. That is to say, the device must be capable of being directed in any direction whatever at any time or be continuously revolved during operation.

In an embodiment chosen to illustrate the invention and in which these highly desirable features are incorporated there is shown a tower 10, which is preferably constructed in two parts, comprising a lower section 11 and an upper section 12 adapted to be divided or separated at the point 13.

The tower sections each comprise structural forms having essentially the shape of a truncated pyramid, wider at the base than at the top. The lower section 11 may be provided with feet 14 adapted to support the tower upon a supporting surface 15 which may, for example, be a concrete slab or other suitable foundation.

At its upper end the tower section 12 is provided with a horizontal frame 16 to the top of which is applied a platform or plate 17, suitably bolted to the frame 16, having a smooth upper surface. The platform should preferably be provided with an annular flat track 18.

Mounted upon the platform is a box frame, indicated generally by the character 20, which is substantially square in cross-section and has somewhat rectangular sides formed of cross-bracing and vertical struts. The box frame is provided at each corner with a swivel caster wheel 21 adapted to ride upon the track 18. At the top of the box frame there is provided an engine base 22 suitably braced by triangular struts 23 and adapted to support a gasoline or other engine 24 of conventional design.

In this instance, the engine is indicated as a gasoline engine provided with a horizontally disposed drive shaft 25. The drive shaft is connected to a gear housing 26 from which extends a propeller shaft 27 at the outer end of which is a propeller 28. The engine is preferably provided with a suitable casing or hood 29 surrounding the sides and top. A radiator 30 is illustrated as being located at the end of the engine opposite from the location of the propeller.

The engine mounting and box frame are all secured together as one part by suitable bolts or other appropriate connections. The engine and the box frame, therefore, are adapted to rotate as a unit, the engine being balanced upon the box frame so that its weight during operation is properly distributed upon the caster wheels 21.

In order to hold the box frame in a rotating position upon the platform and track, there is provided a central rotating shaft. In this embodiment, a cylindrical shaft 35 of relatively large diameter has been utilized. The cylindrical shaft is provided with a flange 36 at the top to which is bolted a plate 37 completely covering the upper end of the cylindrical shaft. The plate is here shown as forming a bottom plate for the engine base and provides a means of attaching the top of the cylindrical shaft to both the engine base and the top of the box frame. The cylindrical shaft is centerably disposed within the box frame.

The plate or platform 17 has at its center a circular aperture 38 slightly larger in diameter than the outside diameter of the cylindrical shaft and serves as a journal bearing for the shaft at a point intermediate its upper and lower end.

At the lower end of the shaft there is provided a bearing 40, the casing of which is mounted upon a horizontal beam 41. In this particular embodiment, a bearing ring 42 engages a collar 43 which is fastened to a bottom 44 of the cylindrical shaft. By constructing the bearing in the manner shown the bearing serves both as a thrust bearing and a journal bearing. Cooperation of the bearing 40 and the journal bearing effect of the aperture 38 serves to rotatably center the cylindrical shaft at the top of the tower and thus permit it to rotatably anchor the box frame and engine in place. The weight of the engine and the box frame is sufficient to hold it down in a satisfactory manner upon the platform.

In this embodiment, it has been found advantageous to utilize the cylindrical shaft 35 as a fuel tank for the storage of gasoline which is supplied in a conventional manner to the engine 24. For filling the tank there is provided a filler spout 45 at the top of the box frame equipped with a suitable cap 46. It will be observed that the cylindrical shaft, which serves as a tank, rotates with the box frame and engine as a part of the box frame-engine assembly.

In order to drive the box frame and engine unit through a rotating cycle, power may be taken from the drive shaft of the engine and utilized as a means of rotation. The parts selected for the utilization of engine power in this manner comprise a ring gear 50 bolted to the platform 17 by suitable bolts 51, the ring gear being provided with teeth 52 at the outside circumference, said circumference being of relatively large diameter. The ring gear, of course, remains stationary disposed on the platform 17.

Meshing with the ring gear is a gear or pinion 53 keyed to a driven shaft 54, the driven shaft being suitably journaled by well-known means upon the box frame and by a journal bearing 55 at the top of the engine base. At its upper end the driven shaft is provided with a bevel gear 56 meshing with a corresponding bevel gear 57 which forms part of a gear reduction mechanism 58. The gear reduction mechanism is connected through gears 59 and 69 to the drive shaft 25. In this manner rotation of the engine drive shaft, which may be at a relatively high speed, is transferred through the gear reduction mechanism in a manner permitting rotation of the driven shaft 54 at a relatively low speed. The low speed operation of the driven shaft 54 is further reduced by cooperation of the small gear or pinion 53 with the ring gear 50.

Inasmuch as it is customary to start air propellers at full load, it is not felt necessary to provide the engine with a clutch. Speed of operation is controlled entirely by adjustment of a conventional throttle. Starting of the engine may be accomplished by resort to the usual storage batteries and self-starter, not shown.

In order that the self-starter and throttle control may be manipulated entirely by a person standing on the ground at the base of the tower, there is provided means for passing mechanical controls or electrical controls, as occasion may require, downwardly from the engine and box frame.

In this particular embodiment, a hollow tube 60 is located centerably within the hollow shaft 35. The tube is anchored to a sleeve 61 on the top plate 37 and extends in sealed relationship through the collar 43. The lower end of the tube terminates in a control box 62 located adjacent the base of the tower. Engine control cables 63

for the throttle and 64 for the starter, for example, originate in the control box 62, extend upwardly through the tube 60 and emerge at the top. The cables may be passed over suitable idler pulleys 65, 66 and 67, the pulleys 65 being mounted in the sleeve 61 and the pulleys 66 and 67 being carried by a bracket 68. The cables 63 and 64 may then be led from the idler pulleys 67 to the conventional throttle and self-starter, not shown.

It should be noted that the tube 60 forms an integral part of the cylindrical shaft 35 and is adapted to rotate with the cylindrical shaft and the box frame-engine assembly. Rotation being at a relatively low speed makes adjustment of the controls in the similarly rotating control box 62 a relatively simple matter.

When the device is shipped, it is customary to break the tower into its upper and lower sections 12 and 11 and crate them separately. The box frame can likewise be crated separately as can also be the engine. For convenience, the cylindrical shaft 35 with the tube 60 removed can be used as a receptacle for shipping the propeller 28. The tube 60, which can be ordinary pipe, is adapted to be provided in sections short enough to be shipped with the cylindrical shaft.

When the device is erected, the tower sections are first assembled one above the other, and the cylindrical section may then readily be mounted in place upon its bearing in the upper tower section. By use of a suitable lift the box frame may then be located upon the platform and centered upon the cylindrical shaft, following which the engine may be mounted and bolted in place securing it to both the box frame and the upper end of the cylindrical shaft. When the cables 63 and 64 are connected to the appropriate motor parts, threaded through the tube 60 and attached within the control box 62, the device is ready for operation.

Normally, it will be necessary only to operate the self-starter which sets the entire device in operation and then to control its speed by means of the cable attached to the throttle. There may, however, be occasions wherein it is desirable to disconnect the drive from the engine to the ring gear so that the propeller will continuously project air in one direction only. Should this be required, a conventional type clutch may be interposed between the drive shaft 25 and the driven shaft 54 and a clutch cable attached thereto and run through the tube 60 in the same manner as are the cables 63 and 64.

Customarily, the propeller will rotate relatively slowly so as to push a large volume of air outwardly at only a moderate velocity sufficient to break up the strata of air without actually creating what may be termed a "wind." The continual circulation of air will be sufficient to break up the strata, and whether the propeller projects air in one direction only or whether it projects air continuously throughout a 360° arc, air will be moved away from the tower in the direction of propeller projection, and movement of air in this manner will tend to draw air from strata either above or below the top of the tower into the propeller stream. Operation of the device will affect a considerable within a radius centering about the tower location.

By providing an air circulating device comprising prefabricated parts of rugged and simple construction, as shown, there is provided an inexpensive wind tower which may be erected at any desirable location in an orchard or other fruit growing area.

Although the invention has been herein shown and described in what is conceived to be the most practical and preferred embodiment, it is recognized that departures may be made therefrom within the scope of the invention, which is not to be limited to the details disclosed herein but is to be accorded the full scope of the claims so as to embrace any and all equivalent structures.

10. The invention having been herein described, what is claimed and sought to be secured by Letters Patent is:

1. An air circulating device comprising a tower and a platform at the top, a box frame having rollers adapted to traverse the platform, an engine centrally balanced on the box frame and a propeller driven by said engine, and a support for said box frame resistant to lateral thrust comprising a shaft extending through the box frame and the platform, one end being attached to the box frame and the other end being in rotational engagement with the tower adjacent the location of said rollers intermediate top and bottom thereof.

2. An air circulating device comprising a tower having a lower pyramidal section including a base, an upper pyramidal section having a bottom fitting the top of the lower section and a platform at the top, a box frame having rollers adapted to traverse the platform in the plane of the upper face thereof, a combustion engine centrally balanced on the box frame and a substantially horizontally directed propeller driven by said engine, and a support for said engine and said box frame resistant to lateral thrust comprising a vertical shaft extending through the box frame and the platform attached at one end at the top of the box frame and at the other end to the tower intermediate top and bottom thereof, said shaft having a rotating engagement with the platform in substantially the same plane as the upper face of the platform.

3. An air circulating device comprising a tower, a frame rotatably mounted at the top of the tower, an engine and propeller device on the frame, and a shaft for securing the frame to the tower comprising a fuel tank, said shaft having points of attachment respectively to the frame and to the tower at a location remote from the top, one of said points of attachment being a rotatable connection.

4. An air circulating device comprising a tower, a box frame rotatably mounted on the top of the tower, a combustion engine and propeller device balanced centerably on the box frame, and means for securing the box frame to the tower comprising a cylindrical shaft having closed bottom and top forming a fuel tank, the top of said tank being fixedly attached at the box frame and a bearing attaching the lower end of said shaft to the tower, said tower having an aperture therein providing a journal bearing in contact with the cylindrical shaft.

5. An air circulating device comprising a tower, a platform on the top of said tower, a box frame rotatably mounted on the platform, a combustion engine and propeller device balanced centerably on the box frame, and means for securing the box frame to the tower comprising a cylindrical shaft having closed bottom and top forming a fuel tank, the top of said tank being fixedly attached at the top of the box frame and a combined anchor and rotation bearing attaching said bottom to the tower at a location

remote from the top of the tower, said platform having an aperture therein providing a journal bearing in contact with the cylindrical shaft intermediate the ends thereof.

6. An air circulating device comprising a tower, an engine base rotatably mounted on the tower, a combustion engine and propeller device mounted on the base, and means for securing the engine base to the tower comprising a cylindrical shaft having closed bottom and top forming a fuel tank, the top of said tank being fixedly attached to the base and a bearing attaching the lower end of said tank to the tower at a location remote from the top thereof, and control connections for the engine extending centerably through the fuel tank and a control box therefor at the base of the tower.

7. An air circulating device comprising a tower, an engine base rotatably mounted on the tower, a combustion engine and propeller device on the base, and means for securing the base to the tower comprising a cylindrical shaft having closed bottom and top forming a fuel tank, the top of said tank being fixedly attached to the base and a bearing attaching the lower end of the shaft to the tower at a location remote from the top thereof, and means for extending controls for the engine to a location at the bottom of the tower comprising a tube extending centerably through the fuel tank and the bearing having an open end above the top of said tank, a control box at the bottom of the tube and control connections between the engine and the control box extending through said tube.

8. An air circulating device comprising a tower, a frame rotatably mounted at the top of the tower and secured against transverse movement with respect thereto, a combustion engine and a propeller device balanced on the frame, a fuel tank connected to the frame and extending

10
15

therebeneath centerably with respect to the tower, said tank being rotatable with the frame and the engine, and means for extending controls for the engine to a location at the lower portion of the tower comprising an extension on the bottom of the fuel tank, a control box and connections traversing the extension and the fuel tank between the engine and the control box.

10
15
20
25

9. An air circulating device comprising a tower, a frame rotatably mounted at the top of the tower and secured against transverse movement with respect thereto, a combustion engine and a propeller device balanced on the frame, a fuel tank connected to the frame and extending therebeneath centerably with respect to the tower, said tank being rotatable with the frame and the engine, and means for extending controls for the engine to a location at the lower portion of the tower comprising a tube extending through the fuel tank having open ends at the top and bottom thereof, a central box at the bottom of the tube and connections extending through the tube between the engine and the control box.
